UNITED STATES PATENT OFFICE

FRED W. BADER, OF HILLSDALE, NEW JERSEY, ASSIGNOR TO J. KRIDEL, SONS & CO., A PARTNERSHIP OF NEW YORK

DESIGN FOR A TEXTILE FABRIC

Application filed August 29, 1930. Serial No. 36,820. Term of patent 7 years.

To all whom it may concern:

Be it known that I, FRED W. BADER, a citizen of the United States of America, and resident of the city of Hillsdale, county of Bergen, and State of New Jersey, have invented a new, original, and ornamental Design for a Textile Fabric, of which the following is a specification, reference being had to the accompanying drawing, forming part thereof.

A single repeatable unit of my design is substantially comprised within the area defined by the lines A B C D, another unit beginning at the intersections indicated at "X".

The figure is a plan view of a textile fabric illustrating my new and ornamental design.

I claim:

The ornamental design for a textile fabric as shown and described.

FRED W. BADER.
